UNITED STATES PATENT OFFICE.

EDWARD J. GULICK, OF MISHAWAKA, INDIANA.

TORSION TUBE-SUPPORT FOR REAR-AXLE HOUSINGS OF AUTOMOBILES.

No. 923,045.

Specification of Letters Patent.

Patented May 25, 1909.

Application filed September 13, 1907. Serial No. 392,693.

To all whom it may concern:

Be it known that I, EDWARD J. GULICK, a citizen of the United States, residing at Mishawaka, in the county of St. Joseph and 5 State of Indiana, have invented certain new and useful Improvements in Torsion Tube Supports for Rear-Axle Housings of Automobiles, of which the following is a specification.

10 My invention relates to means for preventing the housing surrounding the rear axle of a motor vehicle from turning with the inclosed parts. To effect this result I employ a torsion tube connected at its rear 15 end to the casing near the central portion of the same and almost below the main driving shaft. The front end of this tube is connected to the main frame of the machine by a pair of ball and socket joints which give 20 the tube a universal movement. Springs are provided so that the movement of the tube up and down, due to driving the axle forwardly or to applying the brakes, is properly cushioned.

25 I have illustrated the preferred embodiment of my invention on the accompanying sheets of drawing wherein like reference characters refer to the same parts throughout the various views.

30 Figure 1 is a side elevation of my improved torsion tube connection and shows the rear axle in section and the frame of the machine partially broken away; Fig. 2 is a vertical section on line 2—2 of Fig. 1, the 35 frame of the machine being omitted; Fig. 3 is a horizontal section on line 3—3 of Fig. 1; Fig. 4 is a vertical section at the forward end of the torsion tube showing its universal connection with the frame of the machine; 40 and Fig. 5 is a fragmentary plan view of a part of the device shown in Fig. 4.

The automobile or motor vehicle has a main frame including a longitudinal channel bar 10 and a transverse channel bar 11 located some distance in advance of the rear axle 12 and its inclosing housing 13, which has a forward extension 14 containing the speed changing gears of the driving mechanism. The main shaft 15 of the machine is 45 connected to the internal mechanism of casing 13, 14 by a universal joint 16, as is clearly illustrated. As is obvious, it is necessary to provide some means for holding the rear axle casing 13 in position to overcome or 50 neutralize the tendency of the same to rotate

about the axle either forwardly or rearwardly. I therefore provide the mechanism with a bent torsion tube 17 which at its rear end fits within a cylindrical recess 18 of casing 14 nearly below the engine driving shaft 60 15, as is clearly shown in Fig. 2. The outside wall of the recess or aperture 18 is split at 19, the two parts being connected by bolts 20 by means of which the end of the torsion tube may be firmly bound or grasped in its 65 housing recess. By locating the tube in the position shown, it is more nearly beneath the center of gravity of the parts supported thereby than has heretofore been usual, and is therefore more efficiently placed for sustaining the load which it supports.

At the front end of the tube is located a ball or globe 21 having a stem 22 fitted within the tube, as is shown in Fig. 4. The ball 21 is housed within a socket or cylindrical 75 casing 23 having an upwardly-projecting rod extension 24. Socket 23 is hollow and has an opening 25 on the side toward tube 17 for the accommodation of the extension 22 of the ball. Fitted within the lower end of this 80 socket 23 is a concave socket member 26 on which the ball 21 rests, a cap nut 27 being provided for holding the member 26 in place. A transverse pin 28 prevents backing off of the nut. In the upper part of socket 23 I 85 provide a similar concave socket member 29, the concave lower surface of which bears upon the top of ball 21 and is pressed downwardly thereagainst to take up wear by means of a spring 30 interposed between the 90 top wall of the socket or casing 23 and the member 29, as is clearly illustrated in Fig. 4.

The housing 31 having a partially spherical or globular internal lower surface 32 is supported on the transverse channel bar 11 95 by means of an integral bracket 33 secured to the channel by the bolts 34. The upper end of the housing 31 is internally screw-threaded and accommodates a nut 35 having a partially spherical surface 36, the two surfaces 32 and 36 bearing upon an internal hollow ball or globe 37. A threaded hollow dust cap 38 screws on the top of nut 35 and forms a dust-tight joint at 39 to prevent the entrance of foreign substances to the bearing. The dust cap 38 has an hexagonal head 40 for the application of a wrench thereto to screw the same into place. In order that the surface 32 may be adjusted to 100 take up the wear of the parts, the housing or 105 110

casing 31 is split along one side at 41 (Fig. 5), the two parts being bound together by one or more bolts 42. The ball or globe 37 has an aperture 43 extended therethrough 5 and has internal hubs 44 forming bearings for the rod extension 24 which passes through the aperture. At its upper end rod 24 is equipped with a nut 45, and between this nut and the top flat face of the ball or globe 10 37 is interposed a coil spring 46, while between the top end of the socket or casing 23 and the bottom flat face of the ball or globe 37 I interpose a similar spring 47. The opening 48 through the bottom of the housing 31 and the opening through nut 35 are sufficiently large to allow the ball and the 15 rod 24 extended therethrough a considerable movement within its two-part socket bearing.

20 It is obvious from the construction shown and described that the torsion tube 17 may have a limited up and down movement because of the sliding connection of the rod 24 with the ball 37, and that its movement in 25 either direction is cushioned and limited by the springs 46 and 47. The ball and socket joints 21, 26, 29 and 37, 32, 36 provide a universal connection or joint for the forward end of the tube so that it may turn in any 30 direction. This sort of universal joint is necessary because of the relative movement between the frame of the automobile and its rear axle due to the different loads received by the automobile body and to the jarring 35 and vibration of the same when traveling. It is apparent then that I have produced a support for the front end of the torsion tube which permits it to have all the movements necessary and which cushions its movement 40 up or down due to the application of power to the rear axle, and also due to applying the brakes to the same parts. Furthermore, the connection of the rear end of the tube to the casing 13 near the central portion 45 thereof, and nearly below the center of gravity thereof, provides a construction whereby the parts are supported more effectively than in those constructions where the tube is joined or connected to the casing 50 at one side and at some little distance from the center of gravity.

It will be obvious to those skilled in the art that various changes may be made in the structural details shown and described without departure from the substance and heart 55 of my invention.

I claim:

1. In a motor-vehicle, the combination of a rear axle housing, a machine frame, a torsion tube fastened to said housing at its rear end, and a pair of ball and socket joints between the front end of said tube and said frame, substantially as described.

2. In a motor-vehicle, the combination of a rear axle housing, a machine frame, a torsion tube fastened to said housing at its rear end, and a ball and socket joint between the front end of said tube and said frame, the socket of said joint comprising a pair of concave members one of which is spring 70 pressed toward the ball between them, substantially as described.

3. In a motor-vehicle, the combination of a rear axle housing, a machine frame, a torsion tube fastened to said housing at its rear end, a ball and socket joint supported by said frame, the ball of said joint having an aperture therethrough, and a rod connected to the front end of said torsion tube and extended through said aperture, substantially as described.

4. In a motor-vehicle, the combination of a rear axle housing, a machine frame, a torsion tube fastened to said housing at its rear end, a ball and socket joint supported by said frame, the ball of said joint having an aperture therethrough, a rod connected to the front end of said torsion tube and extended through said aperture, and a pair of springs interposed between abutments on said rod 90 and the opposite sides of said ball, substantially as described.

5. In a motor-vehicle, the combination of a rear axle housing, a machine frame, a torsion tube fastened to said housing at its rear end, a ball and socket joint supported by said frame, the ball of said joint having an aperture therethrough, a ball and socket joint at the front end of said torsion tube, a socket or casing inclosing said latter ball 100 and socket joint, a rod forming an extension of said socket or casing passing through said aperture, an abutment on the end of said rod, a spring interposed between said abutment and the apertured ball, and another 105 spring interposed between said socket or casing and the opposite side of said apertured ball, substantially as described.

EDWARD J. GULICK.
